UNITED STATES PATENT OFFICE

2,529,048

ONE-PIECE TONGUELESS BUCKLE

Benjamin F. Pease, Jr., Grafton, Mass.

Application March 12, 1949, Serial No. 81,163

1 Claim. (Cl. 24—176)

1

This invention relates to a buckle capable of general application but particularly intended for use on garment-supporting belts.

Such belts are commonly made of leather, and it is one object of the invention to provide a buckle which will not crease nor disfigure a belt at the point where the two ends of the belt are connected.

Another object is to provide an improved one-piece buckle construction so designed that the belt may be conveniently adjusted by using one hand only.

A further object is to provide a tongueless buckle so designed that, when in use, it closely approximates the appearance of a buckle having the usual tongue.

My invention further relates to arrangements and combinations of parts which will be hereinafter described and more particularly pointed out in the appended claim.

A preferred form of the invention is shown in the drawings, in which

Fig. 1 is a partial perspective view of a belt having my improved buckle attached thereto;

Fig. 2 is a longitudinal sectional elevation of the parts shown in Fig. 1;

Fig. 3 is a perspective view of the one-piece buckle; and

Fig. 4 is a perspective view of a part of the buckle and of a spring adapted for use therewith.

Referring to Figs. 1 and 2, my improved buckle 10 is shown in use on a belt B having a reversely folded end portion 12 detachably secured in folded position by snap fasteners 14 and 15. A closed loop or rider 16 is mounted on the belt B and is held from longitudinal displacement by the fasteners 14 and 15, as shown in Fig. 2.

The opposite end portion 20 of the belt B has the usual holes 22 to receive a stud or spur 24 which is fixed on a cross-piece 25 forming the closed end of the buckle 10. The spur 24 projects from the inner edge of the cross-piece 25, as shown in Fig. 2, and a portion 27 of the spur 24 extends partially over the cross-piece 25 and simulates the end of the loose tongue found in the usual two-piece buckle.

At its opposite end, the buckle 10 is provided with separated lugs 30 which extend toward each other and which are received in the end loop 32 of the belt B.

The buckle 10 as described is entirely usable when freely mounted in the loop 32, but adjustment of the buckle is facilitated by providing a spring S (Fig. 4) having a loop portion 40 and having coiled end portions 41. The extreme ends 42 of the end portions 41 are bent inwardly to enter slots 44 in the inner ends of the lugs 30. The tension of the spring S is such as to tend to swing the buckle 10 downward as indicated by the arrow a in Fig. 4.

The two ends of a belt B, constructed as above

2

described, are very easily connected by inserting the belt through the enclosed opening P of the buckle 10, and by allowing the spur 24 to slide along the belt portion 20 until it enters a selected hole 22. The end of the belt portion 20 may then be inserted under the loop or rider 16.

The spring S facilitates entrance of the spur 24 into the selected hole 22 and also acts to resist displacement of the buckle. If it is desired to loosen the belt, the buckle 10 may be swung upward to withdraw the spur 24 from the hole 22 in which it was inserted. The spur 24 will then slide easily along the belt and the spring S will cause the spur to enter the next hole or opening 22.

Particular attention is called to the fact that the spur 24 is substantially perpendicular to the plane of the belt end portion 20 as the belt passes under the cross piece 25 and over the loop 32 at the adjacent end of the belt B. There is thus no tendency for the belt to be creased or otherwise damaged in appearance by any sharp bend around the cross piece 25. Such bending might occur if the spur 24 was at an acute or wedging angle to the plane of the belt.

Having thus described my invention and the advantages thereof, I do not wish to be limited to the details herein disclosed, otherwise than as set forth in the claim, but what I claim is:

30 A one-piece buckle comprising an open rectangular frame member having a relatively broad and flat end member, relatively narrow and elongated integral side members, spaced belt-engaging lugs mounted at the inner faces of the free ends of said side members and directed toward each other, a spur fixed at the inner edge of said end member and directed transversely rearward of said frame member and in a line substantially perpendicular to the line of normal belt strain, 35 and a buckle-tensioning spring having coiled ends mounted on and secured to said end member and directed transversely rearward of said frame member and in a line substantially perpendicular to the line of normal belt strain, 40 and a buckle-tensioning spring having coiled ends mounted on and secured to said end member and directed transversely rearward of said frame member and in a line substantially perpendicular to the line of normal belt strain, 45 and a buckle-tensioning spring having coiled ends mounted on and secured to said end member and directed transversely rearward of said frame member and in a line substantially perpendicular to the line of normal belt strain, an aligned belt opening.

BENJAMIN F. PEASE, JR.
